UNITED STATES PATENT OFFICE.

BENTON C. ROWELL, OF CHICAGO, ILLINOIS.

RAIL-ANCHOR.

1,093,804.

Specification of Letters Patent. Patented Apr. 21, 1914.

Application filed August 4, 1913. Serial No. 782,761.

To all whom it may concern:

Be it known that I, BENTON C. ROWELL, a citizen of the United States, residing in Chicago, in the county of Cook and State of Illinois, have invented a new and useful Improvement in Rail-Anchors, of which the following is a specification.

This invention relates to improvements in rail anchors.

10 An object of the invention is to provide a rail anchor which is made in a single piece, which may be easily applied by unskilled labor, and which will firmly grip the rail at a number of points to prevent the same from 15 slipping relatively to the tie.

The invention furthermore consists in the improvements in the parts and devices and in the novel combinations of the parts and devices as herein shown, described or 20 claimed.

25 In the drawing forming a part of this specification, Figure 1 is a side elevation of a section of rail showing my improved anchor in position thereon. Fig. 2 is a sectional view of the rail and showing in end elevation, the improved anchor and Fig. 3 is a detail sectional view taken on the line 3-3 of Fig. 1.

30 In said drawing, the rail 10 is shown as of usual construction secured to a tie 11 by spike 12.

35 The anchor, designated generally by the reference A, is preferably made as a malleable casting and is provided with a curved, upper gripping surface 13 adapted to engage the under side of the head of the rail, an intermediate curved, gripping surface 14 adapted to engage the upper surface of the rail base and a lower curved, gripping surface 15 adapted to engage the under face of the rail base. All three of the gripping surfaces 13, 14 and 15 are struck on relatively long radii so that when the anchor is tilted or tipped relatively to the vertical as 40 shown in Fig. 1, a wedging action will result between the gripping surfaces and the adjacent faces of the rail. As will be noted, the gripping surface 15 extends substantially horizontally and the gripping surfaces 13 and 14 are disposed at an angle to each other to correspond with the direction of the surfaces with which they engage so that when the anchor is hammered home on the rail the anchor will be securely wedged in place 45 between the base and head thereof. The portions on which the gripping surfaces 13

and 14 are formed are united by a vertically extending portion 16, all the parts being braced by a flange or rib 17. The anchor is provided at the bottom thereof with a depending projection 18, H-shaped in cross-section as shown in Fig. 3, which is adapted to engage with the tie 11 and thereby prevent the anchor and rail from moving relatively to the tie. The portion of the anchor 60 having the gripping surface 15 is provided at its inner end with a bendable tongue 19 which is adapted to be bent and clenched over the inner edge of the rail as shown in Fig. 2.

70 In actual practice, when it is desired to prevent the rail from slipping in the direction indicated by the arrow a in Fig. 1, the anchor will be applied as shown in said figure and in applying the anchor, it will first be hammered in place in a vertical position to wedge the gripping surfaces 13, 14 and 15 transversely to the rail after which the upper end of the anchor will be hammered to tilt the anchor to the position 75 shown in Fig. 1, thereby still further wedging the anchor and rail and after this operation the tongue 19 will then be clenched in position.

75 As will be apparent from the preceding 80 description and drawing, the anchor which I have designed, is adapted to prevent the rail from slipping in either direction by merely changing the position of the anchor 85 relatively to the tie without changing the anchor from one side of the rail to the other. This is an important consideration inasmuch as the anchor should always be placed on the outer side of the rail to avoid any interference with the flanges of the wheels which 90 pass over the track. Furthermore, the arrangement of the gripping surfaces 13, 14 and 15 is such that the upper and lower 95 points of contact are to one side of the central line of the anchor and the point of contact of the intermediate gripping surface 100 is to the other side of said line.

105 From the foregoing description it will be seen that the anchor may be readily applied at any point desired by unskilled labor, that there are three points of gripping contact between the anchor and rail and that any movement of the rail in the direction which the anchor is designed to prevent, serves to increase the grip which the anchor exerts on 110 the rail.

Although I have herein shown and de-

scribed what I now consider the preferred construction of my improvements, yet it will be understood that changes and modifications may be made without departing 5 from the spirit of the invention and all such changes and modifications are contemplated as fall within the scope of the claims appended hereto.

I claim:

- 10 1. A single piece rail anchor having three relatively elongated gripping surfaces adapted to engage respectively the under side of the rail head, the top side of the base and the under side of the base, said 15 surfaces being so arranged that the points of contact between said surfaces and the rail head and under side of the base are located on one side of the central line of the anchor and the point of contact of the 20 third gripping surface is on the opposite side of said line, substantially as specified.
2. As an article of manufacture, a rail anchor having a portion thereof adapted to fit between the under side of the head and 25 top side of the base of a rail, said portion having curved, upper and lower gripping surfaces struck on relatively long radii whereby when the anchor is tilted relatively to the rail it will be wedged thereon, substantially 30 as specified.
3. A rail anchor having three curved, gripping surfaces adapted to engage respectively the under side of the rail head, the upper side of the rail base and the 35 under side of the rail base, all of said gripping surfaces being struck on relatively long radii whereby the anchor grips the rail more firmly as it is tilted from the vertical.
- 40 4. As an article of manufacture, a rail anchor having a portion thereof adapted to fit between the under side of the head and top side of the base of a rail, said portion having curved, upper and lower grip-

ping surfaces struck on relatively long radii, 45 and means extended beneath the rail base and adapted to be clenched thereover for securing the anchor in place, substantially as specified.

5. A single piece rail anchor having three 50 curved, gripping surfaces adapted to engage respectively the under side of the rail head, the upper side of the rail base and the under side of the rail base, all of said surfaces being struck on relatively long 55 radii, the portion of the anchor having the surface adapted to grip the under side of the rail base being provided with an extension having a bendable tongue thereon by which the anchor may be clenched to the 60 rail, substantially as specified.

6. A rail anchor having three curved, gripping surfaces adapted to engage respectively the under side of the rail head, the upper side of the rail base and the under 65 side of the rail base, all of said gripping surfaces being struck on relatively long radii, and means extending beneath the rail base and adapted to be clenched thereto for securing the anchor in place, substantially 70 as specified.

7. A single piece rail anchor having three curved gripping surfaces adapted to engage the under side of the rail head, the upper side of the rail base and the under side of 75 the rail base, said anchor having also a depending projection 18, the gripping surfaces and projection being so arranged that the anchor may be used to prevent the rail from creeping in either direction when applied to the same side of the rail, substantially as specified.

Signed this 1st day of August, 1913, in the presence of two witnesses.

BENTON C. ROWELL.
